UNITED STATES PATENT OFFICE.

MAX POHLMANN, OF BERLIN-SIEMENSSTADT, GERMANY, ASSIGNOR TO THE FIRM: SIEMENS-REINIGER-VEIFA GESELLSCHAFT FÜR MEDIZINISCHE TECHNIK M. B. H., OF BERLIN, GERMANY.

X-RAY SYSTEM.

Application filed November 30, 1926, Serial No. 151,781, and in Germany December 10, 1925.

This invention relates to improvements in X-ray systems, and has particular reference to a system and apparatus for the production of stereoscopic X-ray photographs.

5 In the production of X-ray motion pictures it has been well known to automatically draw a strip of film past an object and to automatically lift off and again apply at least one of the reinforcing sheets to the film.

10 The present invention makes use of a similar contrivance for the production of two exposures for stereoscopic observation that follow one another at such a brief interval of time that stereoscopic pictures can be made 15 of movable objects, such as the lungs and the stomach.

In accordance with the invention the above feature is effected by coupling the drive for the movement of the film and of 20 the reinforcing sheet with a switching device utilized to control two X-ray tubes. The movements of the reinforcing sheet and the film strip are preferably accomplished by the rotation of a motor in opposite directions.

25 In this connection, a movement, that is, as far as possible, free from jerks is to be produced. For this purpose, it is also expedient to utilize springs between the motor and the driven parts.

30 The present construction also admits of the introduction of the reinforcers, the film and the motor in one roll film holder.

The inventive idea involved is illustrated in the accompanying drawings, wherein—

35 Figure 1 is a diagrammatic view of a system and apparatus embodying the invention;

Figure 2 is a partly diagrammatic view showing the arrangement of the film and reinforcing sheet and their connections with the motor;

Figure 3 is a longitudinal section through a film holder showing the apparatus positioned therein; and

45 Figure 4 is a fragmentary plan view, partly broken away and shown in section.

The apparatus shown in Figure 1 includes the switch 1 for controlling the two X-ray tubes 70 and 70', said switch being coupled with switch 2 in the circuit of the motor 3 that moves the film and the reinforcing sheet. A slow-acting relay 5 is utilized for reversing the direction of rotation of the motor; a circuit interrupter 6 controls the length 55 of film to be wound up; and furthermore

an electromagnet 7 is used for the switching on of the tubes and influences the activity of the motor. In addition, a time relay 9 is associated with a winding-up device 10, the latter being controlled through a switch 11, which is also coupled with the switches 1 and 2 and controlled by the operation of the relay 5.

Before the first exposure is made the various parts are in the position shown in Figure 1. If the main controlling switch 12 is now closed a circuit is established from the trunk line 13 through the right-hand contact of the switch 12, a conductor 14, the left-hand contact of the switch 2, the energizing winding 4 of the motor, the right-hand contact of the switch 2, the armature 15 of the motor, the conductor 16, and the conductor 17 to the trunk line 18. The motor begins to operate and develops a moment of rotation in a clockwise direction. Another circuit is temporarily closed from the trunk line 13 through the right-hand contact of the switch 12, the normally closed contacts 19 and 20 of the electromagnet 7, the conductors 21 and 22, the contacts of the circuit interrupter 6, the winding 23 of the relay 5 and the conductors 24 and 17 to the trunk line 18. The relay 5, however, being slow acting, does not attract its armature 43 at this time, due to the fact that another circuit for the electromagnet 7 is established by the closure of the left-hand contact of the switch 12, this circuit extending from the trunk line 18 through said contact, the winding 41 of the electromagnet 7, the normally closed contacts 38 of the time relay 9, and the contacts 56 of the device 10 to the trunk line 13. The electromagnet 7 is thereby energized and attracts its armature 25 to close the contact 37 and thus open the normally closed contacts 19 and 20. The attraction of the armature 25 thereby establishes a locking circuit for the magnet 7 extending from the trunk line 18 through the winding 41 of the magnet, the contacts 38, and the contacts 57 and 58 of said magnet to the trunk line 13. Therefore, the closure of the switch 12 at this time merely sets the motor 3 in motion in a clockwise direction and this motion serves to press the film, which has been previously drawn through by hand, between a movable plate 28 (Figure 2) with a reinforcing sheet 29 and a stationary plate 26 having the reinforcing sheet 27. The plate 26 is connected with the plate 28 by 110

levers 30 which are subject to the action of springs 31 that act to turn the levers in a counterclockwise direction and thereby lift the plate 28 from the plate 26. The plate 28 is connected by means of a band 32 with the drum 33 which is rotatable about the shaft 33' and coupled by means of a gear transmission 65 with a disk 64 loosely placed upon the shaft 34 of the motor 3. This disk 64 is connected with the shaft by a spring 35 (Figure 4) so that in case of rotation of the shaft in the clockwise direction, the disk 64 is carried along by the shaft in consequence of the tightening up in the spring, but is able to yield in case of rotation in the opposite direction, i. e., at the lifting off of the reinforcing sheet. As a result of the rotation of the armature 15 and the drum 33, a pull is exerted upon the band 32 and the levers 30 consequently are turned in the clockwise direction counter to the tension of the springs 31 for the purpose of applying the reinforcing sheets 27 and 29 against the film strip 36. The film and the sheet are then ready for the exposure.

During this time the armature 25 of the magnet 7 has established, through its contact 37, a circuit for the main transformer 71 and the exposure then commences. The duration of the exposure is determined by the adjustment of the time relay 9. When the latter runs down, the contacts 38 are interrupted by the contact 40 which is actuated by the motor 39 of the relay, whereupon the locking circuit for the magnet 7 is opened and said magnet de-energizes. Furthermore, the contact 56 is interrupted by the movement of the motor 39 and the armature 55 of the device 10 coupled with said motor is moved to the dotted line position shown in Figure 1. In consequence of the de-energization of the magnet 7 the circuit for the transformer 71 through the contact 37 is opened and the exposure of the first plate is concluded. The de-energization of the magnet 7 again closes the contacts 19 and 20 whereupon the previously described circuit for the slow acting relay 5 is closed and said relay is energized at this time, due to the fact that the magnet 7 remains de-energized as a result of the opening of the contacts 38. The relay 5 attracts its armature 43 and moves the rod 47 to the left against the tension of the spring 44. Between the switch 1 and spring 44 the rod 47 is provided with a high tension insulation 45. The rod 47 is not firmly coupled with the lever of the switch 1, but, as indicated in the drawing by a hook at the end of the pull rod, in such a way that it can bring about only the movement of the lever to one side, in the direction from right to left in the drawing. This is necessary, since a switching over of the motor has subsequently still to be effected, for the purpose of the pressing on of the reinforcing sheet, by movement of the rod 47 in

the direction toward the right in the drawing, in connection with which switching the tube 70' must not be switched off again. The movement of said rod actuates the switches 1, 2, and 11, opening the latter switch 70 so that the winding 54 of the device 10 is not at this time energized. By the operation of the switch 1 to engage its contact with the left-hand terminal the X-ray tube 70 is disconnected from the transformer 71 and the tube 70' connected therewith. While the tube 70 was in operation during the first exposure the tube 70' received a preliminary heating through the variable resistance 46.

The operation of the switch 2 now closes an obvious circuit through the winding 4 in a different direction from the previously described circuit for said winding, whereupon the motor 3 develops a moment of rotation in a counterclockwise direction and in so doing, by means of the drum 49 which is located on the shaft of the motor and connected with it by a spring 48, draws the film ahead by means of the band 50 after the springs 31 have lifted the plate 28 with its reinforcing sheet 29 off of the film at the cessation of the operation of the motor in the clockwise direction. With the film drum 49 there is coupled, for example by means of a gear train 51, a disk 52 which carries an adjustable contact 53. As soon as the film strip has been drawn ahead the desired length the contact 53 strikes a contact of the interrupter 6 and opens the latter. The circuit for the relay 5 is opened and said relay de-energizes whereupon the rod 47 is drawn to the right by the spring 44. As a consequence of this operation the film movement stops and, in the manner previously described, the reinforcing sheets are pressed on the film by the movements of the contacts 2 to their right-hand position. The restoration of the rod 47 also effects the closure of the switch 11 whereupon a circuit is closed for the energization of the winding 54 of the device 10, which circuit extends from the trunk line 18 through the winding 54, the switch 11, conductor 21, the contacts 20 and 19 and from thence to the trunk line 13. Current flowing through this circuit influences the winding-up device which then moves its armature 55 to the full-line position at which time the contacts 56 are again closed. Since at this time the winding-up operation of the relay 9 is terminated, the contacts 38 are again closed and the previously described circuit for the electromagnet 7 is again established with the result that the primary current for the transformer 71 is again connected thereto through the contact 37 of the magnet 7 and the second exposure then commences. The previously described locking circuit for the magnet 7 being again established the contacts 56 are free to be opened by the movement of the motor 39 of the time relay. The second exposure now proceeds in conformity

with the adjustment of the time relay 9 and terminates when the locking circuit for the electromagnet 7 is opened at the contact 38. The contacts 19 and 20 of the magnet 7 are again closed and the relay 5 energized to attract its armature with the result that the contacts of the switch 2 are shifted to their left-hand terminals and the motor rotates in a counterclockwise direction. The reinforcing plate 28 is lifted from the plate 26 under the influence of the springs 31 and the exposed film is wound up on the drum 49.

The arrangement that has been described for effecting the movements of the reinforcing sheet and of the film by means of the rotation of the motor in opposite directions is used in accordance with a further form of the invention in such a way that the size of the apparatus may be reduced to an extent which will permit of the motor to be mounted in a film roll holder which contains the reinforcing plate and the film, as shown in Figures 3 and 4. The saving in space is attained by the fact that the motor 3 is built into the interior of the film drum 49. Said motor is attached to the one base plate 59 of the holder 60 by means of a frame 61. On an extension of the shaft 34 there is carried a disk 63 which in turn bears the film drum 49. The connection between the shaft extension and the disk 63 is not a rigid one and the film drum is connected with the shaft 34 by the spring 48. The drum 33 is connected with the motor shaft by means of a gear train which is indicated by the wheels 64 and 65 and in this case also the coupling is an elastic one since the gear wheel is not rigidly connected with the shaft, but is joined thereto by means of a spring 35.

This form of construction renders it possible to examine, by means of a luminous screen, an object which is to be photographed before the taking of the picture commences, the observation being made through the reinforcing sheets. The luminous screen 66 is laid upon the middle portion of the holder. The film strip is provided at one end with a paper prolongation which is utilized to draw the film into position for the purpose of examining the object.

What is claimed is:

1. In a system for the production of stereoscopic X-ray photographs, the combination of a movable film upon which successive exposures are made, a motor for moving said film, two X-ray tubes alternately rendered effective when making said exposures, a source of current for said tubes, means operated by said source of current for alternately rendering said tubes effective, and means connecting said source to said motor to drive the same in one direction and operated by the first named means to reverse the direction of said motor when said source is switched from one tube to the other.

2. In a system for the production of stereoscopic X-ray photographs, the combination of a movable film upon which successive exposures are made, a motor for moving said film, two X-ray tubes alternately rendered effective when making said exposures, a source of current for said tubes, means operated by said source of current for alternately rendering said tubes effective, means connecting said source to said motor to drive the same in one direction and operated by the first named means to reverse the direction of said motor when said source is switched from one tube to the other, and time-controlled means governing the operation of the first and second named means.

3. In a system for the production of stereoscopic X-ray photographs, the combination of a movable film upon which successive exposures are made, a motor for moving said film, two X-ray tubes alternately rendered effective when making said exposures, a source of current for said tubes, a switch for alternately connecting said tubes to said source of current, a second switch connecting said source to said motor and operable to reverse the direction thereof, and an electromagnetic device operable at the termination of one exposure for actuating said switches.

4. In a system for the production of stereoscopic X-ray photographs, the combination of a movable film upon which successive exposures are made, a motor for moving said film, two X-ray tubes alternately rendered effective when making said exposures, a source of current for said tubes, a switch for alternately connecting said tubes to said source of current, a second switch connecting said source to said motor and operable to reverse the direction thereof, an electromagnetic device operable at the termination of one exposure for actuating said switches, and a time-controlled device governing the operation of said electromagnetic device.

5. In a system for the production of stereoscopic X-ray photographs, the combination of a movable film upon which successive exposures are made, a reversible motor for moving said film, two X-ray tubes alternately rendered effective when making said exposures, a source of current for said tubes, and means operated by said source of current for alternately rendering said tubes effective and for reversing the direction of said motor.

6. In a system for the production of stereoscopic X-ray photographs, the combination of a movable film upon which successive exposures are made, two X-ray tubes alternately operated to make said exposures, a motor for moving said film, and means including a switching device for alternately operating said tubes and simultaneously reversing the direction of said motor.

7. In a system for the production of stereoscopic X-ray photographs, the combination of a

- of a movable film upon which successive exposures are made, two X-ray tubes alternately operated to make said exposures, a motor for moving said film, means including a switching device for alternately operating said tubes and simultaneously reversing the direction of said motor, and a time-controlled switch for governing the operation of said switching device.
10. 8. In a system for the production of stereoscopic X-ray photographs, the combination of a movable film upon which successive exposures are made, a reversible motor for moving said film, two X-ray tubes alternately rendered effective when making said exposures, a source of current for said tubes, means operated by said source of current for alternately rendering said tubes effective and for simultaneously reversing the direction of said motor, and means for controlling the first named means so that said tubes will be rendered effective during predetermined periods of time.
9. In a system for the production of stereoscopic X-ray photographs, the combination of a movable film upon which successive exposures are made, a source of current, two X-ray tubes adapted to be alternately connected to said source of current, a reversible motor for moving said film, a switching device for said tubes and motor, a time-controlled switch for governing the operation of said switching device, an electromagnetic device controlling the operation of said time-controlled switch, a slow-acting relay 35 for operating said switching device, a circuit for said slow-acting relay extending through contacts of said electromagnetic device, a second circuit for operating the latter device to temporarily render said slow-acting relay ineffective, a third circuit connecting said source of current to one of said tubes and to said motor, said time-controlled switch operating after an interval to close the circuit for said relay to energize the same whereby 40 said switching device is operated to connect said third circuit to the other of said tubes and to reverse the direction of said motor, means thereafter operated by said motor to interrupt the circuit of said relay, and means 45 thereupon operable to again actuate said switching device.

MAX POHLMANN.
